FISH LURE

Adolph C. Westby, Long Beach, Calif.

Application July 10, 1958, Serial No. 51,728

Term of patent 14 years

(Cl. D31—4)

FIG. 1

FIG. 2

FIG. 4

Figure 1 is a left side elevation of a fish lure showing my new design, the right side being substantially like the left side shown;

Fig. 2 is a top plan view of the same;

Fig. 3 is a front elevation of the same; and

Fig. 4 is a bottom plan view thereof.

Stippling on the drawing is shown to indicate merely a contrast in color rather than designating any particular color.

The dominant features of my design reside in the full line portions of the drawing.

I claim:

The ornamental design for a fish lure, as shown and described.
